UNITED STATES PATENT OFFICE

2,659,776

SELECTIVE RECEIVING AND AMPLIFYING
CIRCUIT

Karl Nowak, Vienna, Austria

Application May 13, 1949, Serial No. 93,022

4 Claims. (Cl. 179—171)

1

This invention relates to a device for receiving or amplifying electrical oscillations and in particular to a device wherein a collecting coil of the device is physically located adjacent to the coil of a parallel resonant circuit which is provided in the anode circuit and which is utilized for producing regenerative feed back, this coil being followed by a preferably untuned grid circuit coil, whereby all the coils are mounted on a common support.

In my U. S. Patent No. 2,619,588, issued November 25, 1952, I devised circuits which permit improving the selectivity of the receiving or amplifying means, their essential characteristics being the utilization of degenerative feed back which acts reciprocally in relation to the parallel resonant circuit of the receiving means. This degenerative feed back preferably acts in opposition to the regenerative action in order to obtain a substantial improvement of the selectivity according to the statements made in my former application. The reciprocal effect of the opposed coupling is obtained preferably by connecting the elements which provide the degenerative action in series with a tunable parallel resonant circuit. The effect of the former is opposed to that caused by the regenerative feed back element, in the series circuit, for its impedance is increased for currents of frequencies to which it is tuned.

It was found, by experiment, that the position of the coils relative to each other is of importance. In particular, experiments have shown that the incoming signals should be impressed from the collecting circuit upon the regeneration producing tuned anode circuit of the first stage of the amplifier, rather than upon the coil in its grid or input circuit.

The invention is, therefore, particularly concerned with the design of the input stage of the receiver or amplifier. This special design yields the surprising effect of an improved selectivity, and consequently constitutes an improvement over the invention of the prior application. The explanation of this fact is that, first, the grid of the tube can not be controlled aperiodically, although the circuit connected thereto is, for purposes of economy, an untuned one, while the tuned circuit is inserted in the anode circuit and, second, that undesirable frequencies are eliminated or at least strongly attenuated in response to the reciprocal counter-coupling action.

Accordingly, it is the object of this invention to provide an improved circuit for high selectivity reception of radiated energy in which the energy is first introduced into a parallel tuned circuit in

2

the anode circuit of an amplifier rather than to a coil in the grid circuit.

Another purpose of the invention is to provide an improved circuit for the reception and amplification of radio frequency energy with a high degree of selectivity in which the plate circuit of an amplifier has in series with it a parallel resonant circuit and a degeneration coil, and in which an input coil that may be associated with an antenna is coupled to the inductance in said resonant circuit, said inductance being regeneratively coupled to a coil connected in the grid circuit of the amplifier and the degeneration coil being degeneratively coupled to said grid coil.

It is another object of the invention to improve the selectivity of an input circuit of an amplifier by introducing the signal into a tuned circuit that is connected in the anode circuit of the tube, the inductance coil of the tuned circuit being coupled to a coil in the grid circuit, and a degenerative coil being connected in series with the tuned circuit.

A further object of the invention is to provide a circuit arrangement of the type described in which the grid coil, parallel circuit inductance, the antenna or input coil and the degeneration coil are wound in that order on a common core.

The manner in which these objects are obtained will become apparent from a consideration of the following description in which:

Figure 1 shows a schematic diagram of the circuit that is the subject of this invention, and

Figure 2 shows the relative positions of the various coils in a common core.

In the drawing, Figure 1 shows the circuit in which the coil 2 is included in the grid-cathode circuit of tube 4. This tube may act as radio frequency amplifier or as a detector. The anode path includes in series a condenser 6, coil 8, and the tunable resonant circuit 10 comprised of an inductance 12 and a variable condenser 14. The inductance 12 is arranged to produce regenerative feed back, while degenerative feed back is produced by coil 8. Incoming signals are impressed from the collecting or input coil 16 upon both the coils 8 and 12. As coil 16 is interposed between coils 8 and 12, it will be simultaneously affected by the regenerating action exercised by circuit 10 and the degenerating action of coil 8, and this combined action results in an attenuation of undesirable frequencies. The coil 2 in the grid circuit is energized practically only by coil 12. The result is a high selectivity in addition to good quality of the reception.

The second stage of the amplifier, as shown in

the drawing, Figure 1, is capacitively coupled to the first, whereas resistance 18 which may be replaced by a choke provides a filter for radio frequency currents.

The tunable parallel resonant circuit 10 preferably has one of its terminals directly connected to the cathode of tube 2 or electron discharge device 4.

Figure 2 illustrates the manner in which the different coils 2, 16, 8 and 12 are mounted on a common support which may be a magnetite core, or the like. The coils are wound and mounted adjacent to each other in the following sequence: grid coil 2, tunable circuit coil 12, collecting coil 16, and degenerating coil 8.

Suitable number of turns are:

	Turns
Coil 2	3 to 15
Coil 12	7 to 90
Coil 16	10 to 12
Coil 8	6 to 40

Many other modifications are possible without departing from the spirit and scope of the invention.

Having described my invention, I claim:

1. A device for receiving and amplifying a desired signal comprising a tube having at least a plate, a grid and a cathode, a parallel resonant circuit tuned to the desired signal and having an inductance, a degeneration coil connected in series with said tuned circuit between said plate and said cathode, an input coil inductively coupled to each of said other coils and physically placed between them on a common core so that said inductance and said degeneration coil receive substantially all their energy from said input coil, and a grid coil mounted on said core adjacent said inductance in such manner as to receive substantially all its excitation directly from said inductance.

2. A circuit for improving the selectivity of a

receiving system for a desired signal comprising an electron discharge device having at least a plate, a cathode and a grid, a degenerative coil and a parallel tuned circuit tuned to the desired signal and having an inductance connected in series between said plate and said cathode, a grid coil in circuit relationship with said grid and cathode so as to supply signals appearing therein to said grid, said grid coil being electromagnetically coupled to said tuned circuit so as to receive substantially all of its energy from said tuned circuit, an input coil, said latter coil being coupled to said tuned circuit and said degenerating coil so that said latter coil and said degeneration coil receive substantially all their energy from said input coil.

3. A device such as described in claim 2 in which the coils are mounted in the following order upon a common core, grid coil, the inductance coil of said tuned circuit, input coil and degeneration coil.

4. A device such as described in claim 2 in which the ratio of the turns in the grid coil, the inductance, the input coil and the degeneration coil is 15 to 90 to 10 to 40, respectively.

KARL NOWAK.
